UNITED STATES PATENT OFFICE.

JOHN T. DRUFVA, OF LONGMEADOW, MASSACHUSETTS, ASSIGNOR TO HENRY HYMAN & CO. INC., OF NEW YORK, N. Y., A CORPORATION OF NEW YORK.

PORABLE ELECTRIC LIGHT.

1,287,919.

Specification of Letters Patent. Patented Dec. 17, 1918.

Application filed July 31, 1917. Serial No. 183,653.

To all whom it may concern:

Be it known that I, JOHN T. DRUFVA, a citizen of the United States and a resident of Longmeadow, in the county of Hampden and State of Massachusetts, have invented certain new and useful Improvements in Portable Electric Lights, of which the following is a specification.

The invention pertains more particularly to the character of electric flash lights to be held in the hand and lighted, as occasion may require, by the manual movement of a slide applied upon the exterior casing of the device.

My invention resides more particularly in novel means for completing the circuit between the lamp and battery and in a construction which prevents the accidental circuiting of the lamp by contact with metal articles, such as might arise when a flash light, otherwise constructed, is placed in a box of tools.

The flash light of my invention comprises an exterior casing, a plural cell battery therein, an escutcheon on the side of said casing containing a spring-slide, a conductor of usual type leading to said escutcheon from the negative pole of the battery, a conductor leading from the neighborhood of said escutcheon to the reflector of the lamp and in electrical connection therewith but insulated from said escutcheon by the material of the casing, a metal cap applied upon the upper end of the casing and holding the reflector and lens, a lamp bulb of customary type held by said reflector and engaging the positive pole of the battery, and means on the actuation of said slide in one direction for completing the circuit, said reflector being insulated from the metal parts of said cap and seated upon a ring of insulating material fitting within the same. The reflector at its outer edge engages the lens on a line inwardly from the metal parts holding the lens, and hence the reflector is always out of circuit with said metal parts. The insulating ring seating the reflector insulates the lower portion of the same from the metal parts about the outer end of the lamp, leaving said reflector only in electrical connection with one of the side conductors and with one terminal of the lamp bulb.

The invention will be fully understood from the detailed description hereinafter

presented, reference being had to the accompanying drawings, in which:

Figure 1 is a central longitudinal section, with the wrapping on the battery partly broken away, of a portable flash light embodying my invention;

Fig. 2 is a vertical transverse section through the casing of the lamp and is presented to illustrate more particularly the longitudinal conductors in their relation to the escutcheon and manually operative slide or switch, and

Fig. 3 is a perspective view of the insulating ring upon which the reflector is seated.

In the drawings, 10 designates a fiber casing having a closing cap 11 at its lower end and at its other end a lens 12, reflector 13, electric lamp 14, metal globular cap 15, a metal ring 16 screwed upon said cap and binding the lens 12 against the outer edge of the reflector, and an insulating ring 17 set within the base portion of the cap 15 and receiving, as a seat, the inner side portions of said reflector, the upper edges of said reflector being set inwardly from the ring 16 and engaging the lens 12 along an annular shoulder 18 formed on the inner face thereof. The reflector 13 has a threaded sleeve portion 19 at its inner end, as usual, to receive the threaded body of the lamp 14. One terminal of the lamp is in electrical connection with the reflector 13.

Within the casing 10 is placed a plural cell battery 20 of known type, and within the lower end of the casing and below said battery is confined a coiled conducting spring 21 which is in electrical connection with the negative pole of the battery 20 and also with the lower end of the longitudinal conductor 22 which extends downwardly from the escutcheon 23 to the lower end of the casing 10. The spring 21 performs its usual duty of serving as a conductor and also of pressing the battery in a direction toward the lamp 14.

The escutcheon 23 may be of any suitable type, and it is riveted upon the side of the casing 10, one of the rivets extending through and securing in position the upper end of the conductor 22, which is in electrical connection with said escutcheon. Within the escutcheon 23 is located a switch 24 having an exposed finger-piece and being of any suitable character. The switch 24

may be slid lengthwise of a chamber within the escutcheon 23, and said switch has two spring ends 25, 26, respectively adapted to slide on the casing 10. The switch 25 is made use of to place in circuit with the conductor 22, the upper conductor 27 which is secured at its lower end by an eyelet 28 inclosed within the escutcheon 23 and normally out of electrical connection therewith. The upper end of the conductor 27 is secured in position by a rivet 29 and is in permanent engagement with the reflector 13 at the inner side of the ring of insulating material 17. When the slide 24 is in the position in which it is shown in Fig. 1, its end 25 engages the rivet 28 and thus places the conductors 22, 27 and reflector in electrical connection with one another, but when the slide 24 is moved downwardly in the escutcheon so as to carry its end 25 away from the rivet 28, the circuit between the conductors 22, 27 becomes broken and the light extinguished.

The lower portion of the cap 15 is bent inwardly, as at 30, to form an inwardly extending annular shoulder affording a seat for an annular shoulder 31 formed on the ring 17. The ring 17 at its lower portion is of less exterior diameter than at its upper portion, and this difference in the thickness of the ring creates the shoulder 31; and the lower portion of said ring by reason of its being of less diameter than the upper portion of the ring, may pass downwardly within the outline defined by the shoulder 30, as shown in Fig. 1. The ring 17 by reason of its construction and engagement with the cap 15 may become firmly associated with said cap and maintain the reflector 13 in firm position. The ring 17 insulates the reflector 13 from the cap 15 and also insulates the upper end of the conductor 27 from said cap. The rivet 29 does not extend outwardly through the shell of the tubular casing 10, and hence it is not in electrical connection with the usual sleeve 32 applied upon said casing to receive the threaded lower portion or band of the cap 15. As hereinbefore described the upper edges of the reflector 13 are set inwardly from the metal ring 16 which holds the lens 12 upon the cap 15 and hence said reflector 13 is out of electrical connection with said ring and cap.

The operation of the lamp will probably be obvious from an inspection of Fig. 1. When the slide 24 is moved upwardly to the position shown in Fig. 1, the circuit is

through the rivet 28, conductor 27, reflector 13, and one terminal of the lamp to the positive pole of the battery, and thence from the negative pole of the battery through the spring 21, conductor 22, and escutcheon 23 to the slide 24, then electrically connected with the rivet 28. When the circuit is completed the lamp will be lighted and remain lighted so long as the circuit is maintained. When the slide 24 is moved downwardly from the position shown in Fig. 1, the circuit will be broken at the escutcheon and the light extinguished. When the slide 24 is in its inoperative position, there will be no accidental establishing of the circuit, if the lamp should be placed in a box of tools, by any metal part, such as a file, connecting the escutcheon or slide with the metal parts at either or both ends of the flash light, and this is one of the important results attained by my invention and whereby I produce a flash light in which the circuit is not likely to be made by accidental means, as by placing the same on a metal surface.

What I claim as my invention and desire to secure by Letters-Patent, is:

In a flash light having a casing, rear and forward longitudinal conductors normally separated at their adjoining ends and adapted to be placed in electrical connection by a manually operative switch, and a battery within said casing in electrical connection with the rear conductor, a metal cap applied upon the outer end of said casing and affording at its inner portion an annular shoulder, a reflector within said cap in engagement with the forward conductor and having an electric lamp at its inner end in engagement with the positive pole of the battery, a lens over said reflector, means binding said lens upon said reflector and an insulating ring serving as a seat for said reflector and having above its lower end a shoulder seated upon the aforesaid annular shoulder, the upper edges of the reflector being set inwardly from the metal parts at the outer end of the lamp and said insulating ring also serving to insulate the reflector from said cap.

Signed at Springfield, in the county of Hampden and State of Massachusetts this 27th day of July, A. D. 1917.

JOHN T. DRUFVA.
